UNITED STATES PATENT OFFICE.

GEORG EGLY, OF BERLIN-TREPTOW, GERMANY, ASSIGNOR TO GEBRÜDER SIEMENS & CO., OF BERLIN-TREPTOW, GERMANY, A GERMAN COPARTNERSHIP.

FLAME-ARC LAMP AND ELECTRODE THEREFOR.

1,221,039.

Specification of Letters Patent.

Patented Apr. 3, 1917.

Application filed November 26, 1915. Serial No. 63,626.

To all whom it may concern:

Be it known that I, GEORG EGLY, a citizen of the German Empire, and residing at Berlin-Treptow, Germany, have invented 5 certain new and useful Improvements in Flame-Arc Lamps and Electrodes Therefor, of which the following is a specification.

This invention relates to flame-arc lamps and electrodes therefor of the type described 10 and claimed in the U. S. Patent No. 1,132,313. In this patent I have described a flame-arc lamp in which the formation of slag on the negative electrode is prevented by incorporating salts of the alkalis in the negative electrode as an essential constituent 15 evenly distributed throughout the entire mass thereof.

According to my present invention I employ boracic acid instead of salts of the 20 alkalis.

It has been found that boracic acid prevents the formation of slag still more effectively than borates or other salts of alkalis and that the light of the arc is still steadier. 25 The advantage of boracic acid is found to be particularly great in open arc-lamps, whereas in inclosed arc-lamps the resulting advantage is less marked. It has been found that the beneficial action occurs only when 30 the amount of the admixture exceeds a cer-

tain limit depending on the percentage of salt in the positive electrode. The correct proportion must be found experimentally in each case. For example, when positive carbons are used containing about 30 to 40 per cent. of luminous salts it has been found that about 3 to 5 per cent. of ordinary boracic acid are required according to the nature of the luminous salts in each case, or a correspondingly smaller quantity when 35 the anhydrite is employed.

My invention is diagrammatically represented in the accompanying drawing, wherein *a* denotes the upper or positive, and *b* the lower or negative electrode. The former 45 contains an admixture of light-emitting salts, while the latter contains a suitable proportion of boracic acid as an essential ingredient.

Having thus described my invention I 50 claim as new and desire to secure by Letters Patent of the United States:—

A flame-arc lamp comprising in combination a negative electrode, containing as an essential ingredient a slag preventing admixture in the form of boracic acid evenly distributed throughout the mass of the said electrode, and a positive electrode containing luminous admixtures. 55

GEORG EGLY.
